TRAILER COACH

Harlan L. Spencer, deceased, late of Syracuse, Ind., by Effie P. Spencer, Syracuse, Ind., and The National Bank and Trust Company of South Bend, South Bend, Ind., administrators, and Clement T. Beeson, Bremen, Ind., assignors to Liberty Coach Company, Inc., Bremen, Ind., a corporation of Indiana

Application December 5, 1950, Serial No. 13,268

Term of patent 7 years

(Cl. D14—3)

To all whom it may concern:

Be it known that Harlan L. Spencer, deceased, late citizen of the United States, residing in Syracuse, in the county of Kosciusko, State of Indiana, and Clement T. Beeson, a citizen of the United States, residing in Bremen, in the county of Marshall, State of Indiana, did invent a new, original, and ornamental Design for Trailer Coach, of which the following is a specification, reference being made to the accompanying drawing, forming part thereof and wherein;

Fig. 1 is a top plan view of the new design for trailer coach;

Fig. 2 is a view in elevation of the right side thereof;

Fig. 3 is a front elevation;

Fig. 4 is a rear elevation;

Fig. 5 is a view in horizontal section taken substantially along the section line 5—5 of Fig. 6, parts being broken away for convenience of illustration; and

Fig. 6 is a view in vertical section taken substantially along the section line 6—6 of Fig. 5, parts being broken away for convenience of illustration.

The characteristic features of the design reside in those parts and their relationship and configuration as shown in full lines in the drawing.

We claim:

The ornamental design for a trailer coach, substantially as shown and described.

EFFIE P. SPENCER,
Co-Administrator with the will annexed of the Estate of Harlan L. Spencer, Deceased.
THE NATIONAL BANK AND TRUST COMPANY OF SOUTH BEND,
By ROLAND W. GOHEEN,
Vice-President and Trust Officer as Co-Administrator with the Will Annexed of the Estate of Harlan L. Spencer, Deceased.
CLEMENT T. BEESON.
